PLASTIC COATED SHEET MATERIAL

Richard A. Mazur, McFarland, Wis., assignor to United States Rubber Company, New York, N.Y., a corporation of New Jersey

Filed Jan. 14, 1966, Ser. No. 670

Term of patent 14 years

(Cl. D87—3)

The figure of the drawing is a plan view of a plastic coated sheet material showing my new design.

A single repeat of the design is enclosed within the quadrilateral figure bounded by the broken lines in the drawing.

I claim:

The ornamental design for a plastic coated sheet material, as shown.
